CLAIM

The ornamental design for a compact inhaler, as shown and described.

DESCRIPTION

FIG. 1 is a front perspective view of a compact inhaler, wherein the compact inhaler includes a cover enclosing a first open end of the compact inhaler, and wherein a canister is inserted in a storage position in a second open end of the compact inhaler, the canister forming no part of the claimed design;

FIG. 2 is a bottom perspective view of the compact inhaler; FIG. 3 is a back perspective view of the compact inhaler; FIG. 4 is a front view of the compact inhaler;

FIG. 5 is a back view of the compact inhaler;

FIG. 6 is a side view of the compact inhaler;

FIG. 7 is a top view of the compact inhaler;

FIG. 8 is a bottom view of the compact inhaler;

FIG. 9 is an opposite side view of the compact inhaler; and, FIG. 10 is a front perspective view of the compact inhaler, wherein the cover is removed from the first open end, and wherein the canister is removed from the second open end and inserted in a ready position in the top open end, the canister forming no part of the claimed design.

In all of the figures, the dash-dash broken lines in the drawings depict portions of the compact inhaler that form no part of the claimed design. The dot-dash broken lines depict the canister in the environment and form no part of the claimed design.

1 Claim, 5 Drawing Sheets
